WAVEGUIDE JUNCTION

Charles Edgar Thomas, Jr., Middle River, Md., assignor to The Glenn L. Martin Company, Middle River, Md., a corporation of Maryland

Application July 21, 1952, Serial No. 300,091.

8 Claims. (Cl. 333—8)

This invention relates to a novel waveguide junction especially useful where it is desired to obtain a division of the input energy among several isolated outputs.

It is frequently desirable to obtain radio frequency energy from a single source and to apply predetermined portions of this energy to each of a plurality of separate units. A typical example is where it is desired to supply energy from a local oscillator to each of a plurality of mixers. At the same time it is obviously desirable that the means used to divide the energy will maintain the various mixers isolated from one another so that there will be no unwanted interaction therebetween.

It is an object of this invention to provide a waveguide junction of extremely simple construction and which is adapted to divide energy supplied to the input arm thereof so that one-half of the energy will be caused to travel along one of the output arms and one-quarter of the energy along each of another pair of output arms.

A further object is to provide such a junction which is of extremely compact size and which may be readily matched so as to avoid undesired waves or reflections in the various arms.

A still further object is to provide such a junction which includes means for obtaining the above-mentioned energy disposition, while at the same time providing means for effectively isolating the various output arms from one another.

Further objects and advantages will become apparent from the following description and claims, especially when taken in view of the appended drawing.

In the drawing:

Figure 1 is a perspective view of the waveguide junction; and

Figure 2 is a sectional taken in the plane indicated by the line 2—2 in Figure 1.

As is clearly shown in Figure 1 the waveguide junction comprises six arms 1 to 6, each of which consists of a section of hollow rectangular waveguide. These arms are arranged in opposed pairs, each pair lying along one of three perpendicularly related axes 7, 8 and 9 intersecting at a point 10 interior of the junction. Each of the waveguide sections or arms includes the usual pair of wide walls, or H-plane walls, 11 and a pair of narrow walls, or E-plane walls, 12, the designation of the walls arising from their relationship to the voltage and magnetic fields when the guide is being employed to transmit electromagnetic energy in the dominant or TE-01 mode. Arms 1, 2 and 3 together may be considered as forming an H-plane T, since their broader walls 11 lie in a common plane, similarly, arms 4, 5 and 6 form a second H-plane T with their broader walls lying in a plane perpendicular to that of the other T. The various walls of the arms are interrupted at the junction so that each of the arms has its inner end opening directly, and without obstruction, into the common junction area 13 immediately surrounding the point 10.

In order to match the various arms so that there will be no reflection of energy fed toward the junction through

2

any of the arms the following arrangement is provided. A short metal rod 14 is arranged with its axis parallel to the E-vector of guides 1, 2 and 3 directly opposite the inner end of guide 1 and spaced therefrom substantially as indicated in Figure 2. When this rod is properly located it will serve to match all three arms 1, 2 and 3 so that energy fed into any one of these arms will be distributed as described hereinafter without reflection. A similar rod 15 is arranged with its axis parallel to the E-vector in the guides 4, 5 and 6 to likewise match these three arms. As is well known in the art the length, diameter, and exact location of matching elements 14 and 15 will depend upon the particular range of frequencies that is to be handled by the junction. For example in one such junction using standard one inch by one-half inch waveguide proper matching was obtained over the frequency band from 8500 to 9600 megacycles with the relative sizes and spacings of the matching elements substantially as shown in the drawing. To support rods 14 and 15 an elongated rod 16 is provided, extending along the axis 7 of guides 1 and 4 and being supported at its opposite ends by a pair of rods 17 and 18 located respectively within the guides 4 and 1 and with their axes perpendicular to the E-vectors within these individual guides. With this arrangement the supporting elements 16, 17 and 18 may also be made of metal without appreciably affecting the transmission of energy through the various arms, while at the same time providing a very simple and easily constructed arrangement for supporting the impedance matching rods 14 and 15.

When the above-described junction is properly matched by elements 14 and 15, energy fed into arm 1 will be divided equally between arms 2 and 3, while energy fed into arm 4 will be divided equally between arms 5 and 6. In the first instance none of the energy will appear in arms 4, 5 or 6, while in the second instance none of the energy will appear in the arms 1, 2 or 3. Energy fed into the arm 2 will be divided so that one-half of it will pass into arm 1 and one-quarter into each of arms 5 and 6, with none appearing in arms 3 or 4. Similarly energy fed into arm 3 will be divided among arms 1, 5 and 6, with none appearing in arms 2 or 4. Also, as can readily be seen from the symmetry of the junction, energy fed into either arm 5 or 6 will be divided so that one-half of it goes into arm 4 and one-quarter into each of arms 2 and 3, with none going into the other pair of arms.

In Figure 1, arm 2 has been illustrated as the input arm, while arms 1, 5 and 6 are used as the output arms. Arms 3 and 4 are shown as being terminated by matched loads 19 and 20. The reason for the matched loads 19 and 20 is to insure isolation between the arms 1, 5 and 6. If, for example, arms 1, 5 and 6 are to be connected to mixers, each to receive its proper proportion of energy from a local oscillator applied to the input arm 2, it is obviously desirable that complete isolation be maintained between the various mixers so that there will be no interaction therebetween. For example, if a slight amount of energy were fed back or reflected from the mixer connected to arm 1, this energy would, as previously described, be divided between arms 2 and 3. That energy going into arm 3 would, if the arm were not terminated with a matched load, be reflected and a portion thereof would pass into arms 5 and 6. Obviously under such conditions each mixer would interact with the others. However, when arm 3 is matched any energy coming toward the junction from arm 1 and passing into arm 3 will be absorbed so that none of it can pass into arms 5 or 6. It can likewise be readily shown that any energy arriving through either arms 5 or 6 and passing into arms 3 or 4 will be absorbed and thus will be prevented from coupling into the other output arms.

This junction when properly matched as described will

operate to couple, isolate or divide electromagnetic energy as described above so long as the energy is being propagated therealong in the TE-01 mode, and is consequently usable over a relatively wide band of frequencies. It is extremely compact as manufactured and easily matched. It will be obvious to those skilled in the art that it can be used in many other applications than that of dividing energy for mixing purposes as particularly described. Moreover, while but one particular form of matching has been illustrated, obviously other known matching devices or arrangements could be provided, although that shown has the advantage of being extremely simple to construct, while at the same time permitting a simple but mechanically efficient support therefor. Many other variations will be apparent to those skilled in the art and may be made without departing from the spirit and scope of the invention as defined by the appended claims.

I claim as my invention:

1. A waveguide junction comprising three pairs of axially aligned hollow rectangular waveguide sections, the axes of said pairs being mutually perpendicular to one another and intersecting at a common point, said sections having their inner end portions joined together to form a common enclosed junction area into which each of said sections open, three of said sections having their broader walls arranged parallel to a common plane and the remaining sections having their broader walls arranged perpendicular to said plane.

2. A waveguide junction comprising six sections of hollow rectangular waveguide having their inner end portion joined together to form a common junction area, said sections extending outwardly from said junction area and arranged in opposed pairs, the axes of said pairs lying along three mutually perpendicular axes intersecting at a common point within said junction area, three of said sections having their broader walls lying parallel to a common plane and the other three sections having their broader walls parallel to a second plane perpendicular to said first mentioned plane.

3. A waveguide junction comprising four sections of hollow rectangular waveguide intersecting one another at their inner ends to form a right-angle cross and with their wider walls lying in planes perpendicular to the general plane of the cross, and fifth and sixth waveguide sections having their axes extending perpendicular to the plane of the cross and intersecting the axes of said first-mentioned sections, said fifth section having its wider walls coplanar with the corresponding walls of one pair of said first-mentioned sections and the sixth section having its wider walls coplanar with the corresponding walls of the other pair of said first-mentioned sections.

4. A waveguide junction comprising a plurality of rectangular waveguide sections having H-plane walls, said sections being arranged to form a pair of intersecting H-plane T-junctions, with the planes of the T's perpendicular to one another and with the axes of all of said sections intersecting at a common point within said junction.

5. A waveguide junction comprising a plurality of rectangular waveguide sections having H-plane walls, said sections being arranged to form a pair of intersecting H-plane T-junctions, with the planes of the T's perpendicular to one another and with the axes of all of said sections intersecting at a common point within said junction and means within said junction for separately matching each pair of T's whereby to prevent reflection of electromagnetic energy moving along any of said sections toward said intersection.

6. A waveguide junction comprising six sections of hollow rectangular waveguide having their inner end portions joined together to form a common junction area, said sections extending outwardly from said junction area and arranged in opposed pairs, the axes of said pairs lying along three mutually perpendicular axes intersecting at a common point within said junction area, three of said sections having their broader walls lying parallel to a common plane and the other three sections having their broader walls parallel to a second plane perpendicular to said first mentioned plane, and means within said junction area for matching the impedance of each of said sections to that of said junction.

7. A waveguide junction comprising four sections of hollow rectangular waveguide intersecting one another at their inner ends to form a right-angle cross and with their wider walls lying in planes perpendicular to the general plane of the cross, and fifth and sixth waveguide sections having their axes extending perpendicular to the plane of the cross and intersecting the axes of said first-mentioned sections, said fifth section having its wider walls coplanar with the corresponding walls of one pair of said first-mentioned sections and the sixth section having its wider walls coplanar with the corresponding walls of the other pair of said first-mentioned sections, and a pair of impedance matching rods supported within the common intersection of said sections, one of said rods having its axis perpendicular to the broader walls of said fifth section and the other having its axis perpendicular to the broader walls of the sixth section.

8. A waveguide junction comprising a plurality of rectangular waveguide sections having H-plane walls, said sections being arranged to form a pair of intersecting H-plane T-junctions, with the planes of the T's perpendicular to one another and with the axes of all of said sections intersecting at a common point within said junction and a pair of rectangularly oriented impedance matching rods supported within the common area of intersection of said T's, each rod having its axis perpendicular to the H-plane walls of one of said T's.
